UNITED STATES PATENT OFFICE.

ANDERS JOHAN WIKANDER, OF BROOKLYN, NEW YORK, AND FRITZ JOHANSON, OF PHILADELPHIA, PENNSYLVANIA.

ADJUSTABLE WIRE SCREEN.

No. 844,571.

Specification of Letters Patent.

Patented Feb. 19, 1907.

Application filed December 5, 1905. Serial No. 290,499.

To all whom it may concern:

Be it known that we, ANDERS JOHAN WIKANDER, a citizen of the United States, and a resident of and whose post-office address is No. 442 Pacific street, in the borough of Brooklyn, State of New York, and FRITZ JOHANSON, a subject of the Kingdom of Sweden, and a resident of and whose post-office address is No. 2122 Ontario street, in the city of Philadelphia, State of Pennsylvania, have invented certain new and useful Improvements in Adjustable Wire Screens, of which the following is a specification.

Our invention relates to wire screens, and especially to those intended and adapted to be adjusted and more particularly to those adapted to be rolled up.

The objects of our invention are, first, to provide a strong, durable, efficient, and inexpensive screen; second, to provide a screen capable of adjustment and of being contained in a small space; third, to provide means for adjustment easily and conveniently manipulated. We attain these objects by the means and devices described hereafter, and illustrated in the accompanying drawings, in which like numbers of reference refer to like parts throughout the various views.

Figure 1 is a front elevation of our screen and adjuncts. Fig. 2 is a plan view. Fig. 3 is a side elevation. Figs. 4 and 5 are enlarged views of various parts. Fig. 6 is an elevation showing a modification of our invention. Fig. 7 is a front elevation showing device shown in Fig. 6. Fig. 8 shows an enlarged detail of this modification. Fig. 9 is a side elevation, Fig. 10 is a front elevation, and Fig. 11 is an enlarged detail of another modification. Fig. 12 shows still another modification.

1 represents any casing, such as that of a window, door, or other space where it is desired to set the screen. 1 may also be a separate casing, made especially for the screen and to which the latter is attached.

2 are the intermeshing and interlocking wires constituting the screen itself. We preferably make these in the form of an oval helix.

3 are rings, placed at proper intervals, intermeshing with the wires 2 of the screen and securing the latter to the pin-rod 4, running

lengthwise of the roller 5, which is preferably a pipe.

6 are slots cut in the pipe 5, in which the rings 3 lie. These rings 3 encircle the pin 4 within the pipe 5.

7 are plugs fitting the pipe 5 near each end.

8 is the shaft forming the center of the plug 7 and pipe 5 and running in the bearings at 26. On this is secured at one end the toothed wheel 9, in which meshes the worm 10 on the shaft 11, operated by the sprocket 12.

13^a is a casing covering and containing the wheel 9, the worm 10, and other adjuncts, and sometimes we may construct it to cover the whole screen, as in Fig. 12.

14 is an angle-iron frame in which the screen 2 slides, though we do not limit ourselves to the use of an angle-iron frame. It is evident that wood or other material may be as well employed.

15 is a pin securing the plug 7 to the pipe 5.

16 is a bar or apron forming the bottom of the screen; 17 holes in the bar, into which the helix forming the lower margin of the wire screen is interlooped; 18, holes in bar and lower part of casing or frame by which they can be locked by the insertion of pins.

27 is a rope or chain for operating wheel 12.

19, Figs. 6 and 8, is a disk adapted to be placed upon and firmly secured to the shaft 8 at each end and in place of the gear-wheel 9. 85 20 is an opening in said disk adapted to hold the end of a spring 22, secured at the other end to the pin 21 in the casing or frame.

In Figs. 9, 10, and 11, 23 is a band or tape, of steel or other suitable material, passing 90 over the roller 25 and about the shaft 8, to which it is attached at one end and having at the other end the spring 24. (Shown here only in part.)

Figs. 3, 6, 7, 9, and 10 have the casing 95 broken away in order to show the various operating parts.

The construction and operation of our device is as follows: The angle-iron or wooden frame 14 with the casing 13 13^a may be attached to the frame 1 of an aperture, such as a door or window. Sometimes we make the casing 13^a extend the full length of the roller, so as to almost entirely inclose it, for protection and concealment. The plugs 7 with the shafts 8 are inserted in the tube 5, the plugs

held securely by the pins 15 and the shafts running in bearings on the casing 13. The screen 2, suspended on the roller 5 by the rings 3 lying in the slots 6 and in turn held by the rod 4, is adapted to be rolled up by means of the sprocket and shaft 11 12 operating the worm 10 and gear-wheel 9, attached to the shaft 8 at one end of the roller 5, and in turn operated, if desired, by a chain or rope 27.

10. By making our screen of interlocked or intermeshed wire helices we are enabled to provide a strong yet flexible fabric, and by making the helices of elliptical form the screen is thinner, lies better upon the roller-tube 5, and the wires are less likely to become displaced.

The bar 16, forming the bottom of the screen, slides in the angle-iron frame 14.

As shown in Figs. 6, 7, 8, 9, 10, and 11, we 20 may dispense with the worm-and-gear adjustment and use a spring, by which the screen is rolled up upon releasing the means for securing it in place. These means may be pins inserted in the holes 18 or any other suitable 25 means. The spring shown in Figs. 6, 7, and 8 is a coil-spring, so attached one at each end of the roller 5, as before shown, as to rotate the roller, and thus roll up the screen. In some cases we may prefer to use a tape or 30 band 23, secured to and rolled around the shaft 8 and passing over the roller 25, being secured to a strong helical spring 24, by which tension is applied to the tape and the roller 5 rotated. We do not limit ourselves to these 35 forms of adjustment, as other forms may be utilized to accomplish the same end.

What we claim, and desire to secure by Letters Patent, is—

1. The combination of an angle-iron frame 40 adapted to partially inclose the edges of a screen, a casing superimposed upon the frame and adapted to support and cover a roller, a roller comprising a tube, a shaft and plug secured in each end thereof and adapted to run in bearings in the casing, a plurality of rings lying in apertures in the roller engaging a rod extending longitudinally through the roller, and engaging on the outside a screen composed of a plurality of intermeshed helices having a sash at the bottom, a worm-and-gear adjustment at one end of the roller, covered by the casing and by means of which the roller may be rotated and the screen rolled up or down.

55. 2. The combination of an inclosed casing;

a roller within the casing; a screen formed of a plurality of intermeshed helices; a plurality of rings lying in slots in the roller and engaging the upper helix; a rod extending longitudinally within the roller and engaging the 60 rings; a channel-guide in which the screen slides, and means for raising and lowering the screen.

3. The combination of an inclosed casing; a screen-guide beneath the same; a roller 65 within the casing; a screen formed of a plurality of intermeshed helices; a rod extending longitudinally within the roller; a plurality of rings lying in openings in the roller, and engaging both the screen and the rod. 70

4. The combination of a tubular roller; a plurality of rings lying in apertures in the roller; a screen formed of a plurality of intermeshing helices engaging said rings, and a rod extending longitudinally within the roller 75 and engaging said rings.

5. The combination of a tubular roller; a longitudinal rod within the roller; a screen formed of a plurality of intermeshed helices, and a plurality of rings lying in apertures in 80 the roller, and engaging both screen and rod.

6. The combination of a tubular roller, having a plurality of transverse slots cut therein; a rod extending longitudinally inside of the roller; a plurality of rings in the 85 slots engaging said rod and a screen engaged by said rings on the outside of the said roller.

7. The combination of a tubular roller having slots therein; rings lying in the slots; a pin within the roller, and a screen outside the 90 roller both engaged by the rings.

8. A roller; a screen formed of a plurality of intermeshed helices; a pin running longitudinally within the roller, and a plurality of rings engaging both the screen and the pin. 95

Signed at New York, in the county and State of New York, this 21st day of November, 1905.
